ABSTRACT: Plug-in-type switchgear comprising plug-in support means and a plug-in-type circuit interrupter on said support means with improved means providing contact pressure between the support terminals and the interrupter terminals. The arrangement also provides improved means operable to simultaneously secure the circuit interrupter to the support means and provide contact pressure between the support terminals and the interrupter terminals.

PATENTED JUN 29 1971

SHEET 1 OF 4

FIG. 1

FIG. 7

INVENTOR

Alfred E. Maier

William C. Schiele

ATTORNEY

PLUG-IN-TYPE SWITCHGEAR

BACKGROUND OF THE INVENTION

1. Field of the Invention

Switchgear of the type comprising an insulating support means and a circuit interrupter removably supported on the support means with plug-type terminals of the circuit interrupter in plug-in-type engagement with plug-in-type terminals of the support means.

2. Description of the Prior Art

It is old in the switchgear art to provide insulating support means with terminal conductors on the insulating support means; a circuit interrupter having plug-type terminals thereon; and spring-biased connectors, such as tulip-type spring-biased connectors, connected to the terminal conductors of the support means and cooperable with the plug-type terminals of the circuit interrupter for providing plug-in mounting of the circuit interrupter on the support means. The present invention is an improvement over the prior art in that there is provided by this invention improved means for providing contact pressure between the support terminals and the circuit interrupter terminals. More particularly there is provided by this invention improved means for providing bolted pressure between the support plug-in-type terminals and the circuit interrupter plug-type terminals. Moreover, the same bolts that are utilized to secure the circuit interrupter to the support block serve to provide the bolted pressure between the support plug-in-type terminals and the interrupter plug-type terminals.

SUMMARY OF THE INVENTION

Improved switchgear comprises plug-in support means and a plug-in circuit interrupter removably supported on the support means. The plug-in support means comprises a pair of insulating support blocks for supporting the opposite ends of the circuit interrupter. Each of the support blocks supports a plurality of plug-in-type terminals that extend across the support block in a spaced relationship. Each of the plug-in-type terminals comprises a pair of spaced-bar conductors supported on the support block in a spaced relationship for receiving a plug-type breaker terminal therebetween. A multipole plug-in-type circuit interrupter is supported on the support blocks with the plug-type terminals of the interrupter in plug-in-type engagement with the plug-in-type terminals of the support means. On each of the support blocks there is a separate wedge-type terminal pressure means between each pair of adjacent plug-in-type terminals. Each of the wedge-type terminal pressure means is a toggle structure comprising a pair of insulating members supported in toggle-type engagement. An actuating bar, having a tapped opening therein, is supported under the knee pivot of the insulating toggle. When a bolt member is threaded into the actuating bar and rotated to draw the actuating bar forward, the actuating bar operates on the knee pivot of the insulating toggle to erect the toggle during which movement the insulating toggle members force the adjacent conducting bars apart to thereby provide bolted contact pressure between the terminals of the support means and the terminals of the circuit interrupter. The bolts that are utilized to secure the circuit interrupter to the support blocks are the same bolts that actuate the insulating toggles to provide bolted contact pressure between the plug-in-type terminals of the support means and the plug-type terminals of the circuit interrupter.

BRIEF DESCRIPTION OF THE DRAWINGS

FIG. 1 is a top plan view of plug-in-type support means and a plug-in-type circuit interrupter bolted on the support means;

FIG. 2 is a side elevational view, with parts broken away, and with the circuit interrupter disconnected, of the switchgear of FIG. 1;

FIG. 3 is an end view, with parts broken away, of the switchgear seen in FIG. 2;

FIG. 4 is a bottom plan view of one of the plug-in-type supports seen in FIGS. 1-3;

FIG. 5 is a sectional view taken generally along the line V-V of FIG. 4 looking in the direction of the arrows;

FIG. 6 is a sectional view of the plug-in support as seen in FIG. 5 with a sectional view of the circuit interrupter mounted on the plug-in support and with the terminal pressure means in the bolted contact pressure position;

FIG. 7 is a perspective view of one of the insulating toggles and one of the actuating bars seen in FIGS. 5 and 6.

DESCRIPTION OF THE PREFERRED EMBODIMENT

Referring to the drawings, there is shown, in FIGS. 1-3, plug-in-type switchgear 5 comprising plug-in-type support means 7 and a plug-in-type circuit interrupter 9. The plug-in-type support means 7 comprises a pair of plug-in-type supports 11. Each of the plug-in supports 11 (FIGS. 4 and 5) comprises a molded insulating support block 13 and three-pole-unit plug-in-type terminals 15 supported on the support block 13 in a spaced relationship across the support block 13. Each of the pole-unit plug-in-type terminals 15 comprises a pair of flat faced conducting bars 17 fixedly secured to the support block 13 in a spaced parallel relationship by means of pair of bolt structures 19. As can be seen in FIG. 5, the insulating support block 13 comprises a generally planar front 21 and the block 13 is formed with three cavities 23 open at the front for receiving plug-type terminals in a manner to be hereinafter described. Each pair of bar conductors 17 extends frontward into the cavities 23 (FIG. 5), and backward out past the bottom of the associated support block 11 (FIGS. 2 and 3).

A separate terminal pressure means 27 (FIGS. 4 and 5) is supported on the support block 13 between each of the outer pole-unit terminals 15 and the center pole-unit terminal 15. Each of the terminal pressure means 27 comprises a pair of rigid molded insulating toggle members 29, 31 and a rigid metallic actuating bar 33, which parts are supported on the support block 13 by means of a pair of screws 35 and coil springs 37. As can be understood with reference to FIGS. 5-7, the insulating toggle members 29, 31 are separate members. During assembly of the support means 11, the two insulating toggle members 29, 31 are placed together as shown in FIG. 5 and the actuating bar 33 is placed in a pocket 39 between the toggle members 29, 31. The parts 29, 31, 33 are then moved up into the position shown in FIG. 5, and the two screws 35, with the coil springs 37 supported thereon, are passed up through two openings 41 (FIG. 7) in the actuating bar 33 and through openings between the numbers 29, 31 where the screws are threaded into tapped inserts 43 (FIG. 5) captured in the insulating block 13. With the screws threaded in the position shown on the right in FIG. 5 (the section line V-V in FIG. 4 jogs down through the one screw 35), the coil springs 37, biasing against the actuating bar 33, bias the actuating bar 33 and toggle members 29, 31 upward against the mounting block 13 to thereby support the terminal pressure means 27 on the support block 13 in the position seen in FIG. 5. As can be seen in broken lines in FIG. 5, a leg portion 45 of the toggle member 29 comprises a pivot surface means 47 (FIGS. 5 and 7) that engages similar pivot surface means 47 of a leg portion 49 of the toggle member 31 with the toggle members 29, 31 shown in FIG. 5 collapsed downward in the unactuated position.

The circuit interrupter 9 (FIGS. 1-3) is a three-pole molded or insulating housing-type circuit breaker comprising an insulating housing 51 having a handle 53 protruding through an opening in the front thereof for manual operation. In each pole unit, a pair of cooperable contacts 55 (shown schematically in FIG. 2) are provided to open and close a circuit. In each pole unit, the contacts 55 are in series with conductors 57, 59, that extend toward opposite ends of the pole unit. The circuit interrupter 9 comprises an operating mechanism and trip device of the general type shown, for ex-

ample, in the patent to Stephenson Jr. et al. U.S. Pat. No. 3, 211, 860 issued Oct. 12, 1965. The operating mechanism and trip device are operable to simultaneously operate the contacts 55 of the three-pole units in a well known manner. As is best seen in FIGS. 2 and 6, a separate plug-type terminal 61 is secured to each of the conductors 57, 59 if the three-pole units of the circuit interrupter 9 by means of a nut 63 that is threaded onto a threaded bolt portion 65 of the associated plug-type terminal 61 after the bolt portion 65 has been passed up through an opening in the associated conductor 57 or 59. As can be understood with reference to FIGS. 2, 3 and 6, each of the plug-type terminals 61 comprises opposite parallel generally flat faces for cooperation with the internal flat faces of the spaced bar conductors of the associated plug-in type terminal 15 on the support 13.

As can be understood with reference to FIG. 1, there are four openings through the insulating housing 51 of the circuit interrupter 9 for receiving four mounting bolts 71 that are utilized to secure the circuit interrupter 9 to the support means 7 and to operate the terminal pressure means 27 for providing contact pressure between the plug-in-type terminals 15 of the support means 7 and the plug-type terminals 61 of the circuit interrupter 9.

At a switchboard or panelboard installation the two support blocks 13 are supported on a panel (such as a panel 76 indicated by broken lines in FIG. 3) by means of a plurality of bolts that extends through openings 75 (FIGS. 1 and 4-6) in the support blocks 13. A pair of holes 77 (FIGS. 2) are provided at the bottom end of each of the bar conductors 17. At the switchboard or panelboard installation, a bus bar is positioned between the lower ends of each pair of bar conductors 17 and fixedly secured to the associated pair of bar conductors 17 by means of a pair of bolts that extend through the openings 77 and through openings in the bus bar. Thus, the circuit interrupter 9 can be plugged onto the support means 7 to control the circuits through the bus bars at the installation.

The circuit interrupter 9 is shown in the disconnected position in FIGS. 2 and 3 with the plug-in support means 11 shown in the disconnected unactuated position in FIG. 5. When it is desired to mount the circuit interrupter 9 on the support means 11, the circuit interrupter 9 is moved down onto the front surfaces 21 (FIG. 5) of the support blocks 13 during which movement the plug-type terminals 61 of the circuit interrupter 9 move into plug-in-type engagement with the plug-in-type terminals 15 of the support means 7. Thereafter, the four mounting bolts 71 (FIG. 1) are passed down through the four openings in the insulating housing 51 of the circuit interrupter 9, and each of the bolts is threaded into a tapped opening 79 (FIG. 7) in the associated actuating bar 33. As can be seen in FIG. 5, the insulating toggle members 29, 31 are in the underset position. With the circuit interrupter 9 on the support means 7, the bolts 71 are tightened drawing the actuating bars 33 forward to thereby operate the insulating toggles 29, 31 from the unactuated underset position seen in FIG. 5 to the actuated erected position seen in FIG. 6. As was hereinbefore set forth, the leg portion 45 of the insulating toggle member 29 engages the leg portion 49 of the insulating toggle member 31 at the pivot surfaces 47 (FIGS. 5 and 7). Thus, these leg portions 45, 49 engage at what can be termed a knee pivot 47 of the toggle members. As each actuating bar 33 is drawn upward, the leg portions 45, 49, engaging at the knee pivot 47, are pivoted to the erected position during which movement the surfaces 81 of the members 29, 31 are forced apart to thereby force the associated bar conductors 17 apart. As can be seen in FIGS. 5 and 6, the outer bar conductors 17 of the two outer pole units engage flat surfaces 83 of the insulating block 13 so that these outer bar conductors 17 cannot move outward. Thus, it can be understood that as the toggle members 29, 31 are operated to the erected position shown in FIG. 6 the bar conductors 17 flex and exert contact pressure on the flat sides or faces of the plug-type stab conductors 61. Thus, bolted contact pressure is applied to the plug-in contacts of the switchgear. A separate spring washer 84 is positioned

under the head of each bolt 71 to maintain pressure during expansion and contraction of parts. The bolts 71 serve to fixedly secure the circuit interrupter 9 on the support means 7 and to provide bolted contact pressure between the plug-in-type terminals 15 of the support means 7 and the plug-type terminals 61 of the circuit interrupter 9. When it is desired to remove the circuit interrupter 9, the bolts 71 are operated to force the actuating bars 33 from the position seen in FIG. 6 to the position seen in FIG. 5 during which movement the toggle members 29, 31 are operated from the actuated pressure exerting erected position seen in FIG. 6 to the unactuated underset loosened position seen in FIG. 5. As can be seen in FIG. 6, the bar conductors 17 flex sufficiently to provide contact pressure under the force of the toggle members 29, 31 which are operated by the bolts 71 so that bolted pressure is applied to the plug-in-type terminals by means of the mounting bolts 71 of the switchgear.

Two additional top openings 87 and 89 (FIG. 7) are provided in the bar 33 for receiving mounting bolts of other styles of circuit interrupters that have differently spaced openings therein for receiving the mounting bolts 71.

I claim as my invention:

1. In combination, plug-in support means and a circuit interrupter supported on said plug-in support means, said plug-in support means comprising insulating support means and plug-in type terminal means on said insulating support means, said circuit interrupter comprising a circuit interrupter housing and plug-type terminal means on said circuit interrupter housing, said circuit interrupter removably mounted on said plug-in support means with said plug-type terminal means in plug-in cooperating engagement with said plug-in-type terminal means, mounting and terminal pressure means securing said circuit interrupter to said plug-in support means and providing a contact-pressure bias between said plug-type terminal means and said plug-in-type terminal means.
2. The combination according to claim 1, said mounting and terminal pressure means comprising bolt means securing said circuit interrupter to said plug-in support means and simultaneously providing a bolted contact pressure bias between said plug-type terminal means and said plug-in-type terminal means.
3. The combination according to claim 1, said plug-in support means comprising a generally planar front, said circuit interrupter mounted on said plug-in support means at the front of said plug-in support means with said plug-type terminal means in plug-in cooperating engagement with said plug-in-type terminal means, said mounting and terminal pressure means comprising wedge type terminal pressure means on said insulating support means and mounting bolt means cooperating with said wedge-type terminal pressure means to bolt said circuit interrupter housing to said insulating support means and to simultaneously actuate said wedge-type terminal pressure means to provide a bolted contact pressure bias between said plug-type terminal means and said plug-in-type terminal means.
4. The combination according to claim 3, and said wedge-type terminal pressure means comprising insulating toggle means operated by said mounting bolt means into an actuated erected condition to provide said bolted contact pressure bias between said plug-type terminal means and said plug-in-type terminal means.
5. The combination according to claim 4, said plug-in support means comprising a row of three spaced plug-in-type terminals across said insulating support means in proximity to one end thereof and a row of three spaced plug-in-type terminals across said insulating support means in proximity to the other end thereof, said circuit interrupter comprising a row of three spaced plug-type terminals across said circuit interrupter housing in proximity to one end thereof and a row of three spaced plug-type terminals across said circuit inter-

rupter housing in proximity to the other end thereof, said circuit interrupter removably supported on said insulating support means with each of said plug-type terminals in plug-in cooperating engagement with a separate one of said plug-in-type terminals, said terminal pressure means comprising two insulating toggle-type terminal pressure means supported on said insulating support means in proximity to one end of said insulating support means and two insulating toggle-type terminal pressure means supported on said insulating support means in proximity to the other end of said insulating support means, each of said insulating toggle-type terminal pressure means positioned in a separate space between a center pole plug-in-type terminal and an outer pole plug-in-type terminal, a separate mounting bolt for each of said insulating toggle-type terminal pressure means, each of said separate mounting bolts cooperating with said circuit interrupter housing and the associated insulating toggle-type terminal pressure means to secure said circuit interrupter to said plug-in support means and to erect the associated insulating toggle-type terminal pressure means to a pressure exerting condition whereby the four mounting bolts secure said circuit interrupter to said plug-in support means and simultaneously operate the four insulating toggle-type terminal pressure means to provide bolted contact pressure bias between the six plug-type terminals and their associated six plug-in-type terminals.

6. In combination, multipole plug-in support means and a multipole circuit interrupter on said plug-in support means, said plug-in support means comprising an insulating support block and a pair of pole-unit plug-in-type terminals on said insulating support block in a spaced relationship across said support block, each of said plug-in-type terminals comprising a pair of spaced-bar conductors supported in a spaced relationship on said support block, said circuit interrupter comprising a circuit interrupter housing and a pair of pole-unit plug-type terminals supported in a spaced relationship on said housing in proximity to one end of said housing, said circuit interrupter supported with said one end of said housing on said support block and with each of said plug-type terminals cooperating with a separate one of said plug-in-type terminals with each of said plug-type terminals disposed between the bar conductors of the associated plug-in-type terminal, terminal pressure means on said support block between said plug-in-type terminals, said terminal pressure means comprising insulating wedge-type pressure means between a first bar conductor of one of said pairs of bar conductors and a first bar conductor of the other of said pairs of bar conductors, said plug-in support means comprising means limiting movement of the second bar conductors of bar conductors away from each other, and said insulating wedge-type terminal pressure means being operable to force said first bar conductors away from each other to thereby provide contact pressure between each of said plug-type terminals and the associated plug-in-type terminal.

7. The combination according to claim 6, and said insulating wedge-type terminal pressure means comprising a pair of insulating toggle members operable from an unactuated condition to an erected condition to wedge said first bar conductors away from each other to thereby provide contact pressure

between said plug-type terminals and said plug-in-type terminals.

8. The combination according to claim 7, said insulating wedge-type terminal pressure means comprising an actuating member having a tapped opening therein and positioned opposite the pivot of said insulating toggle members, a bolt member threadedly engaging said actuating member and rotatable to draw said actuating member to an actuating position during which movement said actuating member operates against said pivot to erect said insulating toggle members to provide contact pressure between said plug-type terminals and said plug-in-type terminals.

9. The combination according to claim 8, said bolt member cooperating with said housing and said insulating toggle-type terminal pressure means to secure said one end of said housing to said insulating support block.

10. Multipole plug-in support means for supporting a multipole plug-in-type circuit interrupter, said support means comprising an insulating support block, a pair of pole-unit plug-in-type terminals on said insulating support block in a spaced relationship on said insulating support block for cooperating with a pair of plug-type terminals of said circuit interrupter, each of said plug-in-type terminals comprising a pair of spaced generally flat bar conductors for receiving one of said plug-type terminals therebetween, insulating wedge-type terminal pressure means on said insulating support block between a first bar conductor of one of said plug-in-type terminals and a first bar conductor of the other of said plug-in-type terminals, said insulating wedge-type terminal pressure means being operable from an unactuated position to an actuated position to force said first bar conductors away from each other to provide contact pressure between said plug-in-type terminals and said plug-type terminals.

11. Multipole plug-in support means according to claim 10, said insulating wedge-type terminal pressure means comprising a pair of insulating toggle members supported on said support block between said first bar conductors in an unactuated position, actuating means operable to actuate said insulating toggle members to an actuated erected position wherein said insulating toggle members force said first bar conductors away from each other to provide contact pressure between said plug-in-type terminals and said plug-type terminals.

12. Multipole plug-in support means according to claim 11, said insulating toggle members being in pivotal engagement at a knee pivot, said actuating means comprising an actuating member having a tapped opening therein for receiving an actuating bolt which may be threaded into said tapped opening to draw said actuating member to an actuated position during which movement said actuating member operates against said knee pivot to actuate said insulating toggle members to said actuated erected position.

13. Multipole plug-in support means according to claim 12, said insulating support block comprising a generally planar front for supporting said circuit interrupter, said actuating member positioned with the center line of the tapped opening therein generally normal to said generally planar front whereby said actuating bolt can be operated from the front of said support means to draw said actuating member to the actuated position.
